UNITED STATES PATENT OFFICE.

NELSON SPENCER, OF HONOLULU, TERRITORY OF HAWAII.

WASHBOARD ATTACHMENT.

1,182,226.

Specification of Letters Patent.

Patented May 9, 1916.

Application filed May 11, 1915. Serial No. 27,311.

To all whom it may concern:

Be it known that I, NELSON SPENCER, a citizen of the United States, residing at Honolulu, in the county of Honolulu, Territory of Hawaii, have invented certain new and useful Improvements in Washboard Attachments; and I do hereby declare the following to be a full, clear, and exact description of the invention, such as will enable others skilled in the art to which it appertains to make and use the same.

This invention relates to washboards, and particularly to an attachment for washboards and the like.

15 The object of the invention is to provide an attachment which can be easily applied to a common washboard so that the latter may be firmly supported upon the opposite edges of a bath tub or the like.

20 A further object is to provide such an attachment with means for adjusting the inclination of the washboard.

My invention contemplates an attachment of this character, which is simple, efficient, 25 can be shipped knocked-down in a package in which the parts are compactly disposed, and can be quickly applied to any ordinary washboard.

20 The invention consists in the novel combination and arrangement of parts comprising the washboard attachment, all of which will be hereinafter fully described and pointed out in the appended claims, reference being had to the accompanying drawings, in which—

Figure 1 is a perspective view of an attachment embodying my invention as applied to an ordinary washboard and positioned upon the opposite edges of a bath 35 tub or the like. Fig. 2 is a view of the attachment knocked-down.

Referring to the drawings, the two strips 5 rest upon the opposite edges of the bath tub or the like 6, and a movement lengthwise of said strips is prevented by means of the cleats 7 and 8, which are attached thereto to suit the width of the tub, the cleats 7 being sent loose with the attachment.

40 A clip 9 is slipped over the lower end of each of the side-bars 10^a of the washboard 10, and is clamped thereon by the thumb-screw 11. The rod-bolt 12 passes through the strips 5 and through holes in the clips 9 below the side-bars 10^a, so that the washboard 10 is hinged on the rod-bolt 12 between the strips 5, as shown.

The separator bolt 13 holds the rear ends of the strips 5 at a suitable distance apart, so that said strips are substantially parallel one to the other. An arm 14 is hinged to a each side-bar 10^a of the washboard 10 by a screw 15, and the lower end of each arm 14 engages the top of one of the strips 5 in one of the notches 5^a in said strips, as shown.

The rod-bolt 12 and the separator bolt 13 are furnished in several lengths to suit the various widths of standard washboards.

It will now be noted that the attachment can be easily and quickly applied to any common washboard so as to position the washboard firmly over a bath tub or the like, that the washboard is adjustable angularly, and that the attachment can be shipped knocked-down with its parts compactly disposed.

75 The foregoing description covers one specific embodiment of my invention, while the following claims are definitions of the actual scope thereof.

I claim:

1. An attachment for washboards comprising, a frame consisting of two parallel strips with bolts connecting and separating said strips, said frame adapted to be positioned and supported upon the opposite edges of a tub or the like, means for hinging one end of the washboard between said strips on one of said bolts, and means for rigidly supporting the other end of the washboard on the frame, said means being adjustable 85 to vary the inclination of the washboard.

2. An attachment for washboards comprising, two strips adapted to rest upon the opposite edges of a bath tub or the like, means attached to said strips to prevent 95 movement of the strips lengthwise thereof, clips clamped on the side-bars of the washboard, a bolt passing through the strips and through the clips, a separator connecting the rear ends of the strips, and arms hinged to the washboard, the lower ends of said arms engaging notches in said strips, substantially as and for the purpose described.

3. A washboard attachment comprising two parallel supporting members adapted to 105 extend across a tub or the like and to be supported on the opposite edges thereof, means for pivotally supporting the lower portion of the wash-board on said members, and means for rigidly supporting the upper 110 end of the wash-board on said members, said last-named means being adjustable to

vary the inclination of the wash-board, relative to said supporting members.

4. A wash-board attachment comprising two parallel supporting members, adapted 5 to be positioned on the opposite edges of a tub or the like, means for pivotally supporting the lower portion of the wash-board on said members, and an arm pivoted to each side of the upper portion of the wash-board, 10 each of said supporting members having a

series of notches in any one of which the lower end of the corresponding arm is adapted to engage whereby the inclination of the wash-board may be changed.

In testimony whereof I affix my signature, 15 in presence of two witnesses.

NELSON SPENCER.
